CENTRIFUGAL BLOWER ROTOR

Lester J. Wolfe, Appleton, N. Y.

Application August 16, 1946, Serial No. 691,070

5 Claims. (Cl. 230—134)

1

This invention relates to improvements in fans or rotors for use in connection with centrifugal blowers.

One of the objects of this invention is to provide a fan of simplified and improved construction, the parts of which interfit to facilitate assembly of the same and may then be welded together. Another object of this invention is to provide a fan or rotor for a blower which is made mainly of metal sheets or plates welded together. Another object is to provide a fan having a pair of radially extending blade supporting parts, by means of which the blades of the fan may be accurately welded in correct positions to each other and to a hub. It is also an object of this invention to provide a fan having a substantially cylindrical hub portion having one end thereof constructed to receive a radially extending collar provided with radial slots formed to transmit power to the blades, and a radially extending blade supporting plate which may be welded to the collar and which forms a further support for the blades. Other objects and advantages of this construction will appear from the following description and claims.

In the accompanying drawings which illustrate by way of example one embodiment of this invention:

Fig. 1 is an elevation of a blower housing having a fan or rotor embodying this invention arranged therein.

Fig. 2 is a central sectional elevation of my improved fan or rotor on an enlarged scale on line 2—2, Fig. 1.

Fig. 3 is a fragmentary rear elevation, partly in section, of the fan or rotor.

The fan embodying this invention is primarily intended for use in connection with a blower housing for elevating hay and other coarse materials by means of an air blast, through a discharge spout. It is not intended, however, to limit the fan or rotor to a blower for this particular purpose, since it will be obvious that fans of this type may be used for other purposes. The fan is illustrated in Fig. 1 as used in a housing 4 having an inlet 5 for air and the material to be handled, and having a discharge spout 6.

The fan or rotor is constructed to be secured to an end of a drive shaft 7 which is suitably journalled in the housing 4, and which may be rotated by any suitable or desired drive means (not shown).

The fan includes a hub 9 which may be of any suitable or desired construction. Preferably, however, the hub has a substantially cylindrical

2

outer surface, and an inner bore formed to fit the drive shaft 7. The hub of the fan may, for example, be made of a short length of heavy steel tubing and may be provided with set screws 10 or other suitable means for securing the hub to the shaft 7. The hub is of reduced diameter at the end thereof to which the fan is secured, being provided with an annular recess 12 in the peripheral surface at one end thereof, and a collar 14 is provided which is preferably in the form of a plate of steel or other material that can be welded and is of a thickness equal to the axial length of the recess in the hub. The collar has a central hole or bore which fits snugly in the recess 12 and against the annular shoulder formed at the end of this recess, as clearly shown in Fig. 2. This collar is provided with radially extending slots or recesses, one such slot being provided for each blade 16 of the fan, and the slots 20 are cut accurately in the collar so that the inner end portions of the blades 16 may be accurately positioned with reference to the hub by means of the collar. The collar may be completely formed by means of a single stamping operation or may be otherwise cut from a flat piece of metal.

The collar and hub may be welded together in any suitable or desired manner. For example, the adjacent edges of the hole in the collar and 30 of the end of the shaft may be provided with an annular groove in which the welding may be done as indicated at 17 in Fig. 2. Welding may also be done at the opposite face of the collar at the outer face of the bushing 9. By means of 35 this welded construction, the collar and hub become a substantially integral part, so that no key or other securing means are required to connect the hub and collar.

The fan or rotor also includes a blade supporting and reinforcing plate 18 which may be of any desired exterior shape or contour and is preferably also made of a flat metal plate. The blade supporting plate may, for example, be provided with outwardly extending legs 19 which are 45 provided with radial slots 20 into which portions of the blades 16 may fit. The blade supporting plate preferably fits flush against the end of the drive shaft 7 and against the end of the hub 9 as shown in Fig. 2, and consequently the axial portion of this plate does not have a bore through which the shaft 7 extends.

In order to provide a strong and rugged construction, the slots 20 in the blade supporting plate extend only a part of the distance from the 50 outer ends of the legs 19 and the blades 16 are

provided at their inner ends with slots into which unslotted portions of the arms 19 of the plate 18 extend, so that the slotted portions of these blades may engage opposite faces of unslotted parts of the blade supporting plate 18. The portions of the blades adjacent to the slots therein and to the inner portions of the blades enter the slots in the collar, and since the collar is welded to the blade supporting plate, a very secure connection is provided between the blades and the parts of the fan on which they are supported and this connection is of ample strength to transmit the power of the drive shaft to the blades. The inner ends of the blades may be arranged in spaced relation to the hub 9, but preferably the blades extend to the hub so that the inner edges of the blades engage or are in close proximity to the peripheral surface of the hub 9. The blade supporting plate 18 and the blades 16 are also made of flat metal and can be punched from a plate or sheet by means of dies, or otherwise cut so that all of these parts may be accurately assembled.

In the assembly of the fan or rotor, the collar 14 is first fitted on the recessed end of the hub 9, which will automatically bring the collar in concentric relation to the axis of the hub and the collar may then be welded to the hub in any suitable or desired manner. The blade supporting and reinforcing plate 18 and the blades 16 are then fitted to the collar 14 by the interfitting slots of the blades and of the supporting plate, and the inner portions of the blades are then inserted into the radial slots formed in the collar 14, for example by moving the supporting plate against the end of the collar 9. The supporting plate may then be welded to the collar 14 in any usual or suitable manner, for example, by forming a weld around the peripheral portion of the collar and the portion of the supporting plate adjacent thereto as indicated at 24, Fig. 3. The blades of the fan may then be welded to the supporting plate and collar along the meeting edges thereof, as indicated at 25. If the blades are so formed that the inner edges thereof lie against the outer surface of the hub member 9, then these inner edges of the blades may also be welded to the outer surface of the hub by means of longitudinally extending welds 21, Fig. 3.

By means of the construction described, the various parts of the fan can be readily assembled so that they occupy correct positions relatively to each other and the parts can be quickly welded together to form a strong and rigid fan. While the blades 16 in the construction illustrated are flat, they may, of course, be of any other suitable or desired contour. By means of the construction described, the fan may be made entirely of steel so that all of the parts thereof can be welded together, and provide ample strength and freedom from connections or joints that may become loose. The collar 14, together with the supporting plate, form a strong support for the blades at the portion thereof nearest to the axis of the hub 9, where the blades and other parts of the fan are subjected to the greatest stresses. At greater distances from the axis, beyond the collar 14, the supporting plate 18 alone is sufficient to carry the torque of the driving shaft to the blades. Beyond the blade supporting plate 18, the blades themselves have sufficient strength to withstand the stresses to which they are subjected. The collar also prevents warping of the supporting plate during welding. Because of the

welded joints at the slots in the blade supporting plate, the collar and the blades, the slots in these parts, which facilitate the accurate assembly of the fan, do not weaken the structure.

5 I claim:

1. A rotary fan formed for mounting on a drive shaft and including a substantially cylindrical hub having an annular recess in the peripheral surface at one end thereof, a radially outwardly extending collar having an axial aperture into which said recessed end of said hub fits, a weld securing said collar to said hub, a blade supporting plate arranged in contact with said collar and the adjacent end of said shaft, and welded to said collar, said collar and said plate having coinciding radial slots, and fan blades extending into said slots and extending outwardly from said plate and collar and welded to said plate and said collar, and means for securing said hub on a shaft.

2. A rotary fan formed for mounting on a drive shaft and including a substantially cylindrical hub having an annular recess in the peripheral surface at one end thereof, a radially outwardly extending collar having an axial aperture into which said recessed end of said hub fits, a weld securing said collar to said hub, a blade supporting plate arranged in contact with said collar and the adjacent end of said shaft, and welded to said collar, said collar and said plate having coinciding radial slots, and fan blades extending into said slots and extending outwardly from said plate and collar and welded to said plate and said collar, means for securing said hub on a shaft, the inner ends of said blades being welded to said hub.

3. A rotary fan for mounting on a drive shaft and including a substantially cylindrical hub, a radially outwardly extending collar welded to said hub, a blade supporting plate welded to said collar, said collar and said plate having registering slots extending inwardly from the outer edges thereof, a plurality of blades having parts extending into said slots and welded to said plate and said collar, and means for securing said collar to a drive shaft.

4. A rotary fan according to claim 3 characterized in that said fan blades have slots extending inwardly from the inner ends thereof and that the blade supporting plate has slots in the outer portions only thereof, whereby the slots in the blades receive unslotted portions of said plate and the slots in said plate receive unslotted portions of said blades, and in which the welded connections extend along said slots.

5. A rotary fan for mounting on a drive shaft and including a substantially cylindrical hub, a radially outwardly extending collar welded to said hub and having slots therein extending inwardly from the periphery of said collar toward said hub, a blade supporting plate secured to said collar, said plate having slots extending inwardly from the outer edge thereof and terminating radially beyond said collar, said plate being secured to said collar with the slots in said collar and said plate in alignment, the portion of said plate which is secured to said collar being free from slots, and a plurality of blades having parts extending into said slots of said plate and said collar and having the inner portions thereof slotted to straddle the unslotted portions of said plate, said blades being welded to said plate and to said collar.

LESTER J. WOLFE.
